GASKET CUTTER

William Wagner, Brooklyn, N. Y.

Original application April 1, 1949, Serial No. 84,796. Divided and this application December 30, 1949, Serial No. 136,104.

6 Claims. (Cl. 30—178)

1

This invention relates to a notch cutter for gaskets of refrigerator doors and the like. This is a divisional application, the original application having been filed by applicant on April 1, 1949, under Serial No. 84,796, now Patent No. 2,493,513.

Refrigerator door gaskets are manufactured in continuous strips or lengths which must be cut to appropriate size to fit the doors of the many different makes, sizes and styles of refrigerators now on the market. They must also be notched at appropriate points for the purpose of forming corners and also for the purpose of enabling the gaskets to follow the contours of doors with curved sides or edges. A 90° corner requires a 90° notch in the gasket and a gentle curve necessitates the formation of a plurality of acute angle notches in the gasket. The problem of providing suitable notches, accurately spaced and precisely placed is not very serious in the plants where refrigerators are made, since in long production runs of gaskets for a given size and type of refrigerator prefabrication or pre-notching is the keynote. The problem does attain substantial proportions, however, when the repairman or serviceman in the refrigeration field is called upon to substitute a replacement gasket for the one with which the refrigerator was originally equipped. The serviceman has to contend with a great many types and makes and sizes of refrigerators. He must also contend with many types of gaskets. And his problem is to incorporate the proper type of notch in the right place in each individual case.

It is clear, therefore, that servicemen have had to take time consuming measurements and that they have also had to engage in considerable guesswork in order to fit a given gasket to a given refrigerator door. They have had to lay out each gasket for pre-notching before mounting the gasket on the refrigerator door. Improvised tools have been devised for assisting in this work but these tools have invariably been awkward to use and their accuracy has been considerably less than desired and required. In short, no gasket notcher has heretofore been devised which is adapted to cut a notch of suitable size in precisely the right place and in accurate angular alignment. Efforts have also been made to notch the gasket during the process of mounting it on the door so that each notch would be cut as its appropriate location is reached. Satisfactory notching means have not, however, heretofore been devised for doing this kind of work and although this would be the ideal method of affixing

2

a replacement gasket to a refrigerator door, the method has not heretofore been in wide use for want of a suitable tool to notch the gasket directly on the refrigerator door.

It is the principal object of this invention to provide a gasket notcher which may be applied to a gasket during the course of the process of affixing it to a refrigerator door. The gasket notcher of the present invention functions in the manner of a pair of cutting pliers or nippers. It may be held in one hand precisely as a pair of pliers is held and it may be used very conveniently in the precise location where a corner or notch is required.

Another object of this invention is the provision of a notch cutter of the character described which includes gasket aligning means for precisely aligning the gasket with respect to the cutter. A guide is provided for the gasket which positions the gasket on a line to which the cutter is perpendicular. An indicator is provided to accurately align the cutter with respect to that point on the gasket which is to coincide with the corner of the door.

Another object of this invention is the provision of a gasket notcher of the character described which has interchangeable cutters for cutting notches of different sizes. In practice, a serviceman may include two or more gasket notchers in his kit, one equipped with a 90° cutter, another with a 45° or 30° cutter and a third with a 15° cutter. If he wishes, however, he may provide himself with a single gasket notcher only, having replaceable cutters of the angular sizes mentioned. The replaceable cutters of the present invention are mounted on individual blocks which are readily secured to one of the jaws of the notcher. A single screw holds each block in place on said jaw and replacement of any one block with another requires simply the removal and then the replacement of said screw.

A further object of this invention is the provision of a gasket notcher of the character described wherein the cutter co-acts with an anvil which is made of softer material than the cutter and which is replaceable at will. The cutter is made of hardened steel and the anvil is made of a relatively soft material such as pressed wood, which is held in place by a single screw. The cutter cuts grooves into the anvil and its cutting action with respect to the gasket is thereby enhanced.

A still further object of this invention is the provision of a gasket notcher of the character described wherein a soft mat is placed beneath

the anvil to serve as an equalizer therefor and to compensate for any qualities in the cutter. For example, should one of the blades of the cutter reach the anvil before the other blade, the anvil will tilt accordingly so that when full pressure is applied to the cutter, its two blades will bear against the anvil with equal force.

The invention herein claimed has thus far been described in terms of its application to a refrigerator door gasket. This, however, should be taken as illustrative of the many functions and purposes of the present invention. The invention is well adapted for other applications, but for the purposes of convenience and clarity, the specification will be limited to its use in connection with gaskets for refrigerator doors.

Preferred forms of this invention are shown in the accompanying drawing in which:

Fig. 1 is a side view of one form of this invention, wherein the cutter is non-adjustable, the blades of said cutter being affixed to the upper jaw of the notcher;

Fig. 2 is a plan view of said gasket notcher, looking downwardly upon the upper jaw and upon the projecting portion of the lower jaw;

Fig. 3 is a view similar to that of Fig. 1 showing the jaws of the notcher in open position and showing a refrigerator door gasket lying on the anvil and against the guide;

Fig. 4 is a fragmentary view looking up in the direction of the upper jaw and showing the fixed cutter thereon;

Fig. 5 is a fragmentary view looking downwardly upon the lower jaw showing the anvil thereon;

Fig. 6 is a view similar to that of Fig. 1 of a second form of this invention wherein the cutter is mounted on a replaceable block;

Fig. 7 is a view similar to that of Fig. 4 showing a block attached to the upper jaw of the notcher and carrying a pair of cutting blades which are situated at an angle of approximately 30° with respect to each other;

Fig. 8 is a similar view of a replacement block on which the blades are disposed at an angle of approximately 60° with respect to each other;

Fig. 9 is a similar view of another replacement block on which the blades are disposed at an angle of approximately 90° with respect to each other;

Fig. 10 is a fragmentary view of a refrigerator door gasket wherein a 90° notch has been cut with the aid of one of the notchers of the present invention;

Fig. 11 shows how said gasket is folded at the apex of said notch to form a 90° corner;

Fig. 12 is a view of another strip of refrigerator door gasket wherein a plurality of equally spaced notches of approximately 30° have been formed by means of the cutter shown in Fig. 7;

Fig. 13 shows how said gasket is turned in at each said notch to form a substantially regular curve conforming to the curvature of a given refrigerator door; and

Fig. 14 is an enlarged fragmentary sectional view of a notcher made in accordance with the design shown in Figs. 1 to 4 inclusive, wherein a cushion is placed beneath the anvil to serve as an equalizer with respect to the cutter.

The simplest form of this invention is shown in Figs. 1 to 5 inclusive of the drawing. It comprises a pair of cooperating handles 20 and 21 respectively which are pivotally connected to each other by means of rivet 22. The upper handle 20 extends downwardly past the rivet to

form a lower jaw 23 and lower handle 21 extends upwardly past the rivet to form upper jaw 24. As Figs. 2 and 4 clearly show, upper jaw 24 is triangular in shape, the apex 25 of the triangle on a vertical plane on which the longitudinally axes of the two handles are situated. The triangle under discussion is a right angle isosceles to whose base line the handles of the device are perpendicular. Extending downwardly from the two side edges of the triangular jaw 24 is a pair of flanges 26 and 27, respectively. Mounted on said flanges by means of screws 28 is a pair of cutting blades 29 and 30, respectively, which comprise the cutter of the tool under discussion. It will be seen that these two cutting blades are disposed at right angles with respect to each other and that they meet to form an apex or vertex 31 immediately adjacent to, and in line with apex 25 of the jaw proper.

It will be seen in Figs. 2 and 5 that the lower jaw 23 is also substantially triangular in shape but it will also be seen that it has a forwardly extending, substantially rectangular portion 35 which has an upwardly extending flange 36 formed thereon. Flange 36 is disposed on a vertical plane to which the longitudinal axis of the tool (on which apices 25 and 31 are disposed) is perpendicular. A centrally disposed indicator 37 is formed on flange 36 in line with apices 25 and 31. It will be seen in Fig. 6 that the floor of lower jaw 23 supports a board of pressed wood 38 which is screwed thereon by means of screw 39. This board serves as the anvil which the cutter is adapted to strike. The anvil, like jaws 23 and 24, is substantially triangular in shape.

The blades of the cutter are made of hardened steel and they retain their sharp cutting edge for a very long time. Nonetheless, they are replaceable either for sharpening or replacement purposes, since they are held on the upper jaw solely by means of screws 28. Anvil 38 is made of relatively soft material, such as pressed wood or plastics. The blades of the cutter are adapted to cut into the anvil without doing themselves injury in order to produce a clean cut in the gasket. The anvil is also readily removable from the tool for replacement purposes since it is fastened to the lower jaw thereof solely by means of a single screw 39.

Fig. 3 shows the position which rubber gasket 40 assumes when a notch is to be cut into it by means of the cutting tool under discussion. The gasket is placed upon anvil 38 and squarely against flange 36. Flange 36 serves as a guide for squaring the gasket with respect to the cutter and indicator 37 serves as a guide for centering the gasket with respect to the cutter. The tool thus described may be used in the manner of a cutting pliers and its blades 29 and 30 will cut a 90° notch in the gasket. See Fig. 10. The gasket may be folded over at the apex of said notch until the two edges thereof meet thereby forming a square or substantially square corner. The distance between apex 25 and the cutter and guide wall 36 will, of course, determine the depth of the cut. The cutters thus far described may also be used to cut squarely across the gasket by simply holding the gasket between the anvil and only one of the blades, at right angles of said blade. In such case, guide wall 36 will, of course, not be utilized.

Fig. 14 shows that a cushion 45 may be interposed between lower jaw 23 and pressed wood board or anvil 38. Cushion 45 may comprise a sheet of relatively soft and resilient rubber. It

will be understood that the jaws and handles of the tool above described may be made of sand castings and in consequence the two jaws may not line up properly. Cushion 45 serves as an equalizer to compensate for the imperfections in the castings so that if one of the blades of the cutter should be slightly lower than the other and therefore engage the anvil before the other blade engages it, the anvil will tilt accordingly so that equal pressure will be applied to it by both blades.

The form of invention shown in Figs. 6 to 9 inclusive is somewhat similar to the form of invention first above described except that its cutter is connected only indirectly to the upper jaw, whereas in the first form of the invention, it is fastened directly to it. The gasket cutter now under discussion includes a pair of cooperating handles 50 and 51, respectively, which are pivotally connected by means of a rivet 52. The upper handle 50 extends downwardly across the rivet to form a lower jaw 53 and the lower handle extends upwardly across the rivet to form an upper jaw 54. The lower jaw has a forwardly projecting portion 55 to which an upwardly extending flange or guide wall 56 is connected. A centrally disposed indicator 57 is formed on said guide wall. Removably mounted on the lower jaw is anvil 58. Thus far, this tool resembles the tool first above described and indeed its upper handle and lower jaw are identical.

Upper jaw 54 does not, however, have downwardly extending flanges corresponding to flanges 26 and 27 of the first form of this invention. Instead all it has is a centrally disposed tapped hole adapted to receive a screw 60. A triangular block 61, which is isosceles in character, has a pair of cutting blades 62 and 63 removably fastened thereto by means of screws 64. These blades meet at the apex or vertex of the triangular block and they constitute the cutter of the tool. Several blocks may be provided with each tool. The two sides of block 61 are shown to be disposed toward each other at an angle of approximately 30° at the vertex of said triangular block. Block 70, on the other hand, shown in Fig. 12, is provided with a pair of blades 71 and 72, respectively, which are disposed at an angle of 60° with respect to each other and block 80, shown in Fig. 9, has a pair of blades 81 and 82 which are 90° removed from each other. All three blocks 61, 70 and 80 are interchangeable with respect to jaw 54. When it is desired to cut a 90° notch in the gasket, block 80 is utilized; when it is desired to cut a 60° notch into the gasket, block 70 is used and when a 30° notch is desired, use is made of block 61. If notches of different angular sizes are desired, correspondingly sized blocks should be employed.

Block 61 has a hole formed therein to receive screw 60. To fasten said block to upper jaw 54, all that need be done is to screw it to the jaw by means of said screw 60. Blocks 70 and 80, however, are provided with slots 73 and 83, respectively, in place of the hole in block 61. Screw 60 projects through said slots and it will be understood that said blocks may be positioned at any selected location relative to guide wall 56, in order to control the depth of the cut. In other words, blocks 70 and 80 are adjustable with respect to upper jaw 54 and hence with respect to guide wall 56 and such being the case, deeper or shallower notches may be cut by means of the same tool by simply adjusting the position of said blocks thereon. The apex formed by blades 62 and 63, or by blades 71 and 72, or blades 81

and 82, will normally be lined up with apex 55 of upper jaw 54 and with indicator 57 on guide wall 56. If desired, however, the block may be turned off center so that the two blades mounted thereon will be inclined at different angles with respect to the guide wall 56. It may be found desirable to use the cutter in this manner when a notch whose edges bear at different angles with respect to the longitudinal axis of the gasket is required.

It will be understood that cushion 45 may be used in connection with the gasket cutter last above described in precisely the same manner as it may be used in connection with the gasket cutter first above described. The forms of invention above described illustrate one type of pliers construction and action which may be utilized in the present invention, but it will be understood that other forms of pliers may also be utilized for the purposes of this invention. The foregoing is, of course, descriptive solely of preferred forms of this invention, and it will clearly be understood that these forms may be varied or modified in many ways within the broad scope of the present invention and other forms of the invention may also be had within its broad scope and spirit.

I claim:

1. A notch cutter for gaskets and the like, comprising a pair of co-acting pivotally connected handles, a pair of co-acting jaws on said handles, one of said jaws having a triangular block removably fastened thereto, a pair of cutting blades removably mounted on two sides of said block to describe a V between them, an anvil for said cutting blades mounted on the second of said jaws, and guiding means on said second jaw for locating the gasket on the anvil relative to the cutting blades.

2. A notch cutter for gaskets and the like, comprising a pair of co-acting, pivotally connected handles, a pair of co-acting jaws on said handles, one of said jaws having a triangular block removably mounted thereon, a pair of cutting blades removably mounted on two sides of said cutting block and describing a V between them, a rubber cushion mounted on the second of said jaws, a relatively soft anvil for said cutting blades replaceably mounted on said cushion, and guiding means on said second jaw for locating the gasket on the anvil relative to the cutting blades.

3. A notch cutter in accordance with claim 2, wherein the guiding means for locating the gasket on the anvil is integral with the second jaw and comprises a vertical wall formed on said second jaw adjacent the anvil.

4. A notch cutter in accordance with claim 2, wherein the first-mentioned jaw is provided with a point immediately adjacent the vertex of the V which the two cutting blades describe, and wherein the guiding means for locating the gasket on the anvil comprises a vertical wall formed on the second jaw with an indicator formed thereon, said indicator being located directly opposite the point on the first-mentioned jaw so as to serve as an indicator with respect to the cutting blades mounted on said first jaw.

5. A notch cutter in accordance with claim 1, wherein a cushion is interposed between the anvil and the jaw on which said anvil is mounted, so as to render said anvil adjustable relative to the cutting blades.

6. A notch cutter for gaskets and the like, comprising a pair of co-acting pivotally connected

handles, a pair of co-acting jaws on said handle, a V-shaped cutter removably mounted on one of said jaws, a cushioned anvil for said cutter removably mounted on the second jaw, an indicator on the first jaw immediately adjacent the vertex of the V-shaped cutter, a guide wall on the second jaw for locating the gasket on the anvil relative to the cutter, and an indicator on said guide wall directly opposite the vertex of said V-shaped cutter and the indicator on said first jaw.

WILLIAM WAGNER.
